Inventor:

Van Curan John Hildreth Cary

UNITED STATES PATENT OFFICE.

JONAS NORTHRUP, OF HOPEDALE, MASSACHUSETTS, ASSIGNOR TO HOPEDALE MANUFACTURING COMPANY, OF MILFORD, MASSACHUSETTS, A CORPORATION OF MASSACHUSETTS.

LOOM.

Application filed February 2, 1923. Serial No. 616,484.

To all whom it may concern:

Be it known that I, JONAS NORTHRUP, a citizen of the United States, residing at Hopedale, in the county of Worcester and State of Massachusetts, have invented certain new and useful Improvements in Looms; and I do hereby declare the following to be a full, clear, and exact description of the invention such as will enable others skilled in the art to which it appertains to make and use the same.

The present invention relates to an improvement in looms.

It is the practice of weavers tending automatic bobbin replenishing looms to fill up the magazine or hopper with bobbins and to allow a few spare bobbins to lie on the woven cloth between the fell and the breast beam where they are convenient for insertion in the magazine when the bobbins become exhausted therefrom. This practice occasionally results in a bobbin getting caught between the sand roll and the breast beam frame. Now, it is necessary that a certain amount of space be left between the breast beam and the sand roll in order to convenience the operative in smoothing the cloth as it passes on to the sand roll, so that merely to locate the sand roll close enough to the breast beam so that no bobbins could get caught in the space would be impracticable. Furthermore, to allow the space between the breast beam and the sand roll to be of sufficient width to permit bobbins to pass through would result in causing bobbins to fall down through on to the floor.

The object of the present invention is to produce a construction applicable alike to new and old looms which will prevent the accidental catching of bobbins between the sand roll and the breast beam, and to this end the invention consists in the improvement in looms hereinafter described and particularly defined in the claims.

In the accompanying drawing illustrating the preferred form of the invention, Fig. 1 is a plan of the front of a loom with the present invention applied thereto; and Fig. 2 is a sectional elevation of the sand roll and breast beam with the present invention in place.

The illustrated embodiment of the invention is described as follows: The breast beam 10 of the loom extends from side to side across the front of the loom above the

sand roll 12, over which the cloth 14 passes on its way to the wind-up roll. A fell is indicated at 16 beyond which the threads 18 of the warp are shown. Extending across the loom from selvage to selvage of the woven cloth is a bobbin bar 20. This bobbin bar is riveted to two arms 22 supported on pivots 24 which are received in pivot blocks 26 secured by bolts 28 to the breast beam. Adjusting screws 30 are screwed through the arms 22, and their ends rest upon the top of the breast beam. Set nuts 32 are employed to hold the adjusting screws 30 in adjusted position. The adjusting screws 30 permit adjustment of the position of the bobbin bar to correspond to different positions of adjustment of the sand roll.

The arrangement is such that the bobbin bar 20 is supported close to but slightly above the surface of the cloth passing over the sand roll, so that it does not bear upon nor injure the cloth as it passes by it. The bobbin bar catches any bobbins which may be on the cloth and prevents them from getting caught between the sand roll and the breast beam.

It will be observed that the bobbin bar is pivoted on the breast beam so that when it is desired to lift it to provide access of the operative to the cloth it may be easily and quickly done, and as easily and quickly replaced. This also affords the additional space required to permit the passage of the warp knots when a new warp is put on the loom.

This invention, it will be observed, is applicable not only to new looms, but may be applied as well to old looms and it may be embodied in other forms without departure from the invention herein claimed.

Having thus described the invention, what is claimed is:

1. A loom having, in combination, a breast beam, a sand roll receiving the cloth as it approaches the breast beam, and a bobbin bar supported above the sand roll and adjacent to the breast beam for preventing bobbins from catching between the sand roll and the breast beam.

2. A loom having, in combination, a breast beam, a sand roll supported with its upper surface adjacent to the breast beam, a bobbin bar removably mounted in a position above the sand roll and adjacent to the breast beam.

3. A loom having, in combination, a breast beam, a sand roll supported adjacent thereto, and a bobbin bar pivotally mounted on the breast beam and supported above and close to the surface of the sand roll and near the edge of the breast beam.
4. A loom having, in combination, a breast beam, a sand roll receiving the cloth as it approaches the breast beam, a bobbin bar supported above the sand roll and adjacent to the breast beam for preventing bobbins from catching between the sand roll and the breast beam, and means for adjusting the position of the bobbin bar to correspond to different positions of adjustment of the sand roll.

JONAS NORTHROP.
